RAIL TYING DEVICE

Filed Feb. 12, 1927

Fig. 2.

Inventor:

Stanley W. Finch

Patented May 31, 1927.

UNITED STATES PATENT OFFICE.

STANLEY W. FINCH, OF WASHINGTON, DISTRICT OF COLUMBIA.

RAIL-TYING DEVICE.

Application filed February 12, 1927. Serial No. 167,781.

This invention pertains to rail-tying devices, and more particularly to devices by means of which the rails and ties comprising the major units of what is commonly called a "railroad track" may be fastened together securely.

The device is shown in the accompanying drawings wherein:

Fig. 1 is a side elevation showing the tying device as it appears when in operation in connection with a rail and a tie, the tie being shown in cross section.

Fig. 2 is a view, partly in section, taken on the line 2—2 of Fig. 1.

Fig. 3 is a plan view, partly in section, taken on the line 3—3 of Fig. 1.

In the drawings 1 denotes a steel rail, such as is used in ordinary railway tracks, said rail having a base or flange portion 2.

3 is a tie. 4, 4 are grab hooks one end of each of which hook overlaps an edge of flange 2, the other end of each grab hook having an opening which is preferably square to prevent the turning of the bolt-like member 5, which member 5 preferably has a square shoulder and extends downwardly through the openings in the grab hooks 4 and connects with the tie-contacting element 6.

The preferred means of fastening the rail to the tie by the use of my device involves, as illustrated in the accompanying drawings, a U-shaped tie-contacting element 6 having ears 7 through which the bolts 5 pass and are secured in place by means of the nuts 8 and the washers 9. It is obvious, however, that by using bolts long enough to extend approximately to the bottom of the tie a plain, straight, tie-binding element may be employed in lieu of the U-shaped element shown. The U-shaped element 6 is, however, advantageous because ordinarily the ballast covers the lower portion of the tie and consequently the use of the U-shaped element brings the tensioning means nearer the top of the tie and thus renders it much more convenient to turn the nuts 8 and adjust the tension of the device than when the longer bolts and straight tie-binding element are employed.

In operation the element 6 is placed under the tie directly beneath the rail 1. The two pairs of grab hooks 4, with the bolts 5 in position, are hooked over the edges of the rail flange, the bolts 5 are fastened to the

ears 7 of the tie-binding element 6 by means of the nuts 8 and washers 9. It is obvious that when these various elements are in position as described above, and as shown in the drawings, it is necessary only to turn the nuts 8 in order to secure any desired tension and thus fasten the rail securely to the tie.

The placing the U-shaped element 6 under the tie may be accomplished, when the device is applied to existing roadbeds, by jacking up the tie and sliding the element 6 in the upstanding position shown in the drawing lengthwise along under the tie to its proper position; or, if preferred, a portion of the ballast may be dug away from under the tie and the U-shaped element may be placed on its side and slid endwise under the tie without the necessity of displacing any great amount of ballast, the arms of said member then being raised to the upstanding position shown.

This device may, of course, be applied to existing trackage by the methods above suggested without the necessity of loosening or disturbing in any way the existing means (such as spikes, tie plates, rail joints, etc.) in use for fastening the rails and ties together. Manifestly, therefore, the effect of the use of my present invention is to strengthen, to any desired degree within the limits of the strength of the metal used in the device, the bond between the rail and the tie. The device is, moreover, simple and inexpensive and can be installed on new or existing trackage at a very low cost.

The inventor of this device is aware of the United States Patent No. 1,191,025 covering grab hooks with adjustable connections extending under the tie but believes that his present invention contains elements which constitute a decided improvement over the earlier device by reason of elimination of unnecessary parts, reduced cost, increased strength, and increased facility of application and operation.

What I claim is,—

1. In a device of the class described, grab hooks adapted to embrace a rail flange, a tie-contacting element, bolt-like members adapted tensionally to connect the grab hooks and the tie contacting element, the upper portion of each bolt-like member protruding through openings in the grab hooks.

2. In a rail-tying device, grab hooks each of which has at its lower end an opening

adapted to receive a vertically disposed bolt-like member whereby and in conjunction with tie contacting means and said grab hooks a rail and a tie may be tensionally secured together.

3. In a rail-tying device, grab hooks each of which has at its lower end a perforation adapted for the reception of a vertically disposed bolt-like member, and tie contacting means whereby and in conjunction with the grab hooks and the bolt-like member a rail may be tensionally attached to a tie.

4. A rail-tying device comprising a bolt-like member, opposed grab hooks adapted to engage the edges of a rail flange, each of said grab hooks having at its lower end a vertical opening for the reception of the bolt-like member, and a tie-contacting member whereby and in co-operation with the grab hooks and the bolt-like member a tie may be secured to a superimposed rail.

5. In a device of the class described the combination of a tie, a superimposed rail, tie attachment means, rail-grappling means adapted to embrace the base flange of the rail, and a substantially vertical disposed bolt-like member adapted to extend through aligned openings in the lower ends of the rail-grappling means and through a corresponding opening in the tie-attachment means, whereby the rail and the tie may be tensionally secured together.

6. A device of the class described comprising, in addition to a tie and a superimposed rail, elements of but three types: grab-hooks of substantially identical conformation adapted to embrace therebetween the base flange of the rail, tie-attachment means, and bolt-like means intermediate the grab-hooks and the tie-attachment means, whereby the rail and the tie may be adjustably secured together.

7. A device of the class described comprising, in addition to a tie and a superimposed rail, tie-attachment means, a vertically disposed bolt-like element and a grab-hook element consisting of two parts of substantially identical conformation, one of said elements having an opening through one portion thereof and the other element having a portion adapted to extend through said opening whereby the two elements may be fastened together, and by means of which elements and the tie-attachment means the rail and tie may be adjustably secured together.

8. A device of the class described comprising a tie, a superimposed rail, tie-attachment means partially encompassing the tie, grab-hooks embracing and suspended from the base flange of the rail and having overlapping ends with aligned vertically disposed openings, the tie-attachment means having horizontally-disposed portions with vertically disposed openings in substantial alignment with the openings in the grab-hooks, and bolt-like members adapted to extend through the openings in the grab-hooks and the tie-attachment means whereby and in conjunction with said grab-hooks and said tie-attachment means the rail and the tie may be adjustably secured together.

9. A rail-tying device including tie-attachment means and comprising as one element grab-hooks of substantially identical conformation adapted to clasp the base flange of a rail and as another element a suspended bolt-like member, a portion of one of the elements protruding through a portion of the other element whereby the two elements are fastened together and by means of which elements and the tie-attachment means a tie and a superimposed rail may be adjustably fastened together.

In testimony whereof I have affixed my signature.

STANLEY W. FINCH.
